UNITED STATES PATENT OFFICE.

ALBERT R. HAGER, OF MANILA, PHILIPPINE ISLANDS.

GAME-SCORING DEVICE.

Application filed September 25, 1922. Serial No. 590,430.

To all whom it may concern:

Be it known that I, ALBERT R. HAGER, a citizen of the United States, and a resident of the city of Manila, Province of Rizal,

5 Philippine Islands, have invented a new and useful Game-Scoring Device, of which the following is a specification.

10 My invention relates to a game scoring device which in its preferred form comprises a plurality of relatively long counting pieces which are marked to divide them into several different classes, each class having a specified counting value, and each of the pieces having exposed thereon counting characters which are displayed by dots, the counting value of each piece being directly determined by the number and color of the dots.

15 The scoring device is applicable to games of various kinds but it has been devised primarily for a game in which a great many points are exchanged between players.

20 To illustrate the practical advantages of my device, attention will be directed to the accompanying drawing in which Figure 1 is a view in plan of one class of counters, Figure 2 is a plan view of another class, Figure 3 a plan view of another class, and Figure 4 a plan view of still another class.

25 Referring now to the drawings in detail, I prefer to produce these counting pieces of relatively long and narrow strips (1) of bone, ivory or any other suitable material, preferably of similar appearance suitable to an oriental game, since it is the 30 primary purpose to use these counters with a Chinese game. The pieces are made with substantially flat sides, with either square or rounded corners or edges, so as to leave faces on which the counting characters may 35 be displayed.

40 As above described the counting characters are displayed in dots with different colors used so that each dot of one color may represent one scoring point of the game, with each dot of another color representing one hundred scoring points of the game. 45 Taking the piece shown in Figure 1, first it will be noticed that it includes two dots as at (2). The dots may be placed as shown at each end of the piece and also on both sides of its face, or they may be placed at any other convenient position as desired. 50 Each of these dots is of a color to represent one scoring point of the game, and for these dots I have adopted the color of black but any other color may be used to equal

advantage. On the next piece shown in Figure 2 the dots are grouped in tens, each of a color to represent one scoring point in the game, and with this particular counter thus having a value of ten points. 55 On the piece in Figure 3 one dot is used as at (4) and of a color to represent one hundred scoring points of the game. It so happens that this particular color is red. This particular counter, therefore, has a value of one hundred scoring points. In Figure 4 five dots are used as at (5), these dots being of a color to denote hundreds, consequently this particular counter has a value of five 60 hundred scoring points.

65 The dots need not be necessarily arranged on both display faces of the pieces, or at the respective ends thereof, nor need they be of any particular color, but they should be of different colors to distinguish the value of the scoring points. Then again, as a matter of convenience, I may in some instances use Arabic numbers in combination with the dots, for instance as at (6), on all of the 70 pieces, to make it perfectly clear just what value the dots have.

75 I also prefer to produce the pieces representing the different classes in different lengths.

80 It will be noticed that I form my game scoring device of a plurality of relatively long and thin counting pieces. These stick-like pieces are arranged in series and the pieces of each class differ in length from the 85 pieces of the other classes and each relatively long piece of the same class has at both its ends the same indicating characters. It will 90 also be noticed that each of the indicating characters of each piece correspond in character to the length of the piece to which they are applied. In practice it is manifest the several pieces are adapted by reason of the relatively long or stick-like form thereof to 95 be grasped in a bunch in one hand and when 100 so grasped to expose at the exposed end of the respective pieces the indicating characters thereon, thus facilitating the handling 105 of the scoring devices by the player as well as the bringing of the indicating characters 110 permanently into view so that they can be conveniently selectively picked out of the bunch. It will also be noticed that I provide a scoring device in which the length of the piece corresponds in value to the indicating character upon such piece so that the value of the scoring device is denoted both

by the structural lengths of the piece and by the character thereon.

In playing the game in which this counting device is used, the player in losing two hundred and fifty scoring points to an opponent, would simply hand the winner two of the pieces representing one hundred scoring points, and five of the pieces representing the ten scoring points, shown in Figures 3 and 2 respectively.

Since a number of each class of counting pieces will make up a set an unlimited number of points may be very easily scored without the necessity of using any other counting means.

I claim:

A game counter consisting of a plurality

of relatively long and thin counting pieces arranged in series with the pieces of each indicated value differing in length from the pieces of the other values and each having at both its ends the same value indicating character, each of the indicating characters of each piece corresponding in value with the length of the piece to which they are applied and the several pieces being adapted by reason of the relatively long and thin form thereof to be grasped in a bunch in the hand and when so grasped to cause them to expose at the exposed end of the respective pieces the indicating characters thereon, all substantially as and for the purposes set forth.

ALBERT R. HAGER.
